AUTOMATIC GRAB

Arthur T. Deily, Pittsburgh, Pa., assignor to
 Aluminum Company of America, Pittsburgh,
 Pa., a corporation of Pennsylvania

Application November 4, 1944, Serial No. 561,949

3 Claims. (Cl. 294—67)

1

This invention relates to lifting device of the grab or tong type such as is used for engaging and moving or otherwise handling articles of any configuration but particularly those which are roughly square or oblong in configuration such as trays, baskets, racks, pieces of timber, large metal ingot and the like.

The object of the invention is to provide a lifting device which may be moved from one place to another by means of a crane or hoist and which is more or less automatic in the sense that it will, under proper manipulation, engage and disengage the article to be lifted without manual help.

The attached drawings illustrate in several views a lifting device embodying the principles of the invention, said views being as follows:

Fig. 1 is a top view;

Fig. 2 is a view in side elevation;

Fig. 3 a cross sectional view taken on the line 3—3 of Fig. 1 in the direction indicated by the arrows;

Fig. 4 a top view taken on the line 4—4 of Fig. 3 in the direction indicated by the arrows; and

Fig. 5 a cross sectional view taken at the line 5—5 of Fig. 2 in the direction indicated by the arrows.

Referring to these drawings, in which like numerals designate like parts, the lifting device or grab consists of three main parts: a suitable supporting frame 1, which is preferably square or rectangular in plan and which is adapted to carry all of the cooperating parts of the lifting device, and two side frames which depend from the supporting frame 1 and are pivoted to said frame 1 for swinging motion. Each of the side frames forms, in total, a work engaging or tong or grab arm and consists of a plurality of spaced members 2 which are pivotally connected to the frame 1 and which at their other end are joined together by a channel frame member 3 which not only joins the members 2 into a unit to form the side frame or arm but likewise forms a ledge adapted to support the object grasped by the arms as they are swung into register with said object. In order that the members 2, and therefore the arm of which they are a part, may swing freely, each such member is provided with an inwardly projecting end piece 4 adapted to be mounted, as shown, on shafts 5 and keyed to said shafts. Shafts 5 are mounted on the top of the frame 1 and are there suitably supported in bearings 6. The members 2 which lie at the extremities of each side arm are provided with an upward extension 7, which in turn bears a bolt 8

5 on which is mounted the cross piece 9. Springs 10 are provided at the top of the frame 1 at each end thereof and one end of each spring is fixedly attached to uprights 11 carried in the center of said frame 1, the other end of the springs being attached to the cross pieces 9. Springs 10 are tensioned as by adjustment of the cross-pieces 9 on the bolts 8 so that they tend to pull the cross-pieces toward the center of the frame 1 and thus 10 swing the side arms outwardly.

The device thus described is adapted to be lifted by a hoist or crane which attaches (at two longitudinally spaced points in the specific device shown) to the ring 12, which ring in turn is 15 linked to the swinging arms of the lifting device by the flexible chains 13. It will be apparent that either a single or multiple point suspension may be used and that in a lifting device of the type illustrated in the drawings a balanced two-point suspension is to be preferred. Regardless of the 20 number of points of suspension, the ring 12 and flexible chains 13 are located above and attached to one end of the end pieces 4 of opposite members 2, and at the place where these points of suspension are located the end piece 4 is so shaped 25 as to form a lever or crank whereby force applied upwardly through ring 12 and chains 13 will tend to rotate the members 2 on the shafts 5 and thus close the side arms against the action 30 of springs 10.

Thus it will be observed that if the lifting device rests, for instance, on the floor with one of its side arms on either side of the object to be lifted, said side arms will be swung into the outward position indicated by the dotted line in 35 Fig. 3 and will be maintained in this position by the normal force of the springs 10, which tend to rotate the members 2 outwardly. If, however, force is applied through ring 12 tending to raise 40 the lifting device upwardly, that force, if not otherwise opposed, will tend to rotate the side arms inwardly to the full line position shown in Fig. 3, whereupon the tray 15 or other article which lies between those arms will be grasped 45 by those arms and seated thereon in the manner shown at Fig. 3. Further lifting force applied through the ring by the hoist or crane to which they are attached will maintain the side arms in a work grasping position while the article or tray is moved from one spot to another, but when the lifting device and its contained tray is again placed on a floor and tension from the hoist is eliminated and chains 13 are loosened, the normal action of the springs 10 will automatically 55 disengage the side arms from the tray and return

2

them to the position indicated in dotted line at Fig. 3. In order that the varied positions of the side arms, which are automatically assumed under the conditions above outlined, may be maintained at proper intervals, there is associated with at least one set of corresponding members 2 of each side arm a ratchet mechanism, which is best shown at Figs. 3 and 4. This ratchet mechanism comprises a star wheel 16 keyed to a shaft 17, which shaft is journaled in bearings 18 carried by transverse members of the supporting frame 1. Said star wheel bears projections 19, equally spaced circumferentially, and a like number of recesses 20 between said projections. Pivotedly connected to the opposed members 2 are the plunger rods 21, which are positioned in space by means of apertures in the cross members 29 and the frame 1, through which apertures the plunger rods pass. If desired, each rod may carry at its inner end an adjustable nose piece 22 for such length adjustments as are necessary. The rods 21 are so aligned that their inner ends are adapted to register with either the projections 19 or the recesses 20 of the star wheel 16, depending upon the position of the star wheel at any given moment. The star wheel 16 is rotated to bring its projections or recesses into or out of register with the ends of the plunger rods 21 by means of the ratchet wheel 23 which is keyed to a hub extension of said star wheel. Pawl 24 is mounted to prevent rotation of ratchet wheel 23 in one direction. Movement in the other direction of the ratchet wheel is imparted by lever 25 mounted on shaft 17 which lever is adapted to be raised by means of the flexible connection 26 between the lever and lifting ring 12. The lever 25 carries a spring pressed pawl 27 which is so mounted on said lever that lifting of the lever brings the pawl 27 into position to engage a tooth on the ratchet wheel. Spring 28 is mounted to constantly pull lever 25 downwardly so that when the lifting device is placed upon a floor or support and the flexible chains 13 and the lever operating chain 26 become slack the spring 28 operates the lever 25 pulling the lever and its attached pawl 27 downwardly, thereby indexing the ratchet star wheel 16 to the next position.

The lifting device as illustrated in the drawings has been particularly designed for the lifting of stacked trays such as those shown at 15 and therefore includes refinements not necessary to the operation of the device in its broader applications but particularly useful in that specific application. Included among such refinements are means for insuring that, when the lifting device is placed over the stacked trays and its side arms closed, the arms as they are swinging together will register with the spaces 33 provided in the tray for the entry of the arm ends (see Figs. 3 and 5). Referring to Figs. 2 and 5, this means consists of stop arms 31 pivoted at their upper ends in extensions 32 of the frame 1 and adapted to be swung inwardly so that their ends contact the top of the stacked tray 15 and prevent the lifting device from being lowered beyond a predetermined point. To hold said stop arms 31 in their inwardly swung position removable pins 33 are suitably provided at a proper point in the frame extensions 32. Another refinement are the wheels 34 mounted for free turning movement on shafts 35 at the bottom of each member 2 of each side arm. These wheels merely provide rotating guides when the lifting device bearing the

trays is lowered between confining walls such as the walls of an immersion tank.

The operation of the specific device will now be described. Assuming that the crane operator desires to lift a set of stacked trays 15 and that the lifting device is resting on the floor with its side arms opened outwardly by the normal force of the springs 10, the first step of the operator is to set the star wheel 16 so that its projections 19 are in register with ends 22 of plunger rod 21. So positioned the star wheel 16 will prevent the side arms from closing as the lifting device is raised from the floor by the crane and lowered over the trays 15 because, although the force exerted by the lifting movement through the chains 13 would tend to pull the side arms inwardly against the action of the springs 10, the side arms are held in their outward position by the plunger rods 21 and the pawl 24 operates to hold the ratchet wheel 23 stationary. However when the lifting device is lowered by the operator over the stacked trays and comes to rest thereon as stop arms 31 contact the top of the upper tray (as shown in Fig. 5) and the chains 13 and 25 again become slack the spring 28 pulls lever 25 and its spring actuated pawl 27 downward thus moving ratchet wheel 23 and indexing star wheel 16 so that recesses 20 register with end 22 of the plunger rods. Therefore, the crane operator by taking up the slack of chains 13, and thereby beginning the raising of the lifting device, immediately pulls the side arms inwardly into contact with the stacked trays (as shown in Fig. 3), the plunger arms 21 allowing this movement by pressing into the recesses 20 of the star wheel 16, and the trays may be lifted to another spot. When the trays are to be released the crane operator merely lowers the lifting device to the floor whereupon the slackening of the chain 26 again allows the spring 28 to function indexing the star wheel 16 to where its projections 19 again prevent closing of the side arms as the lifting device is raised from its position around said trays.

Having thus described my invention, I claim:

1. In a lifting device, in combination, a frame, depending side arms pivotally mounted on said frame, means cooperating with said arms to normally and yieldingly force said arms out of lifting position, means for suspending the lifting device from the mechanism for lowering and raising said device, said suspension means being linked to said arms to normally force the arms into lifting position during suspension, a ratchet mechanism, means cooperating with said ratchet to periodically prevent movement of said arms into lifting position and a link connecting the said ratchet mechanism and said suspension means and operable by the suspension operation to cause timed movement of the ratchet mechanism with respect thereto.

2. In a lifting device, in combination, a frame, depending side arms pivotally mounted on said frame, crank extensions on said arms to swing them toward each other into closed position when lifting force is applied to said extensions, spring means for swinging said arms away from each other into open position when said lifting force is removed, suspension means connected to said extensions by which said device is attachable to a raising and lowering mechanism, a pawl and ratchet mechanism carried by said frame, an operating member therefor, a spring for actuating said member in the ratchet operating direction, means actuated by said ratchet mechanism to alternately permit and prevent movement of

said arms into closed position, and means connecting said suspension means and said operating member for moving said member against its said actuating spring upon application of lifting force to said suspension means, to condition said member for subsequently actuating said ratchet mechanism upon removal of the lifting force from said suspension means.

3. In a lifting device, in combination, a frame, depending side arms pivotally mounted on said frame, means cooperating with said arms to normally and yieldingly force the arms out of lifting position, suspension means adapted to suspend the lifting device during each cycle of raising and lowering said device and linked to said arms to normally force the arms into lifting position during suspension, an indexing mechanism adapted to prevent movement of said arms into lifting position during suspension in alternate cycles and means directly linking said indexing mechanism to said suspension means and operable under the application of raising force by said

suspension means to induce an indexing action at the completion of the raising and lowering cycle, whereby the indexing mechanism is positioned to prevent movement of the lifting arms into lifting position during alternate cycles.
